Fig. 1

Fig. 2

Fig. 3

FIG. 1 is a front and right hand perspective view of a combined teleprinter and punched edge card feeder embodying my new design;

FIG. 2 is a front and left hand perspective view; and

FIG. 3 is a rear and right hand perspective view thereof.

This application is a continuation-in-part of my design application Ser. No. D. 13,373, filed Aug. 30, 1968 and now abandoned.

The dominant feature of my design resides in the details and configuration of the punched edge card feeder portion of the design.

I claim:

The ornamental design for a combined teleprinter and

punched edge card feeder, as shown and described.
